ARTICLES OF FURNITURE, SUCH AS BED-
CHAIRS AND BED SETTEESCharles Frech and John Eric Nilsson,
London, EnglandApplication March 29, 1938, Serial No. 198,767
In Great Britain March 14, 1938

13 Claims. (Cl. 5—31)

This invention relates to improvements in articles of furniture, such as bedchairs and bed settees of the kind in which an extension section is normally supported on a main frame to which said section is hingedly or pivotally connected, the section being swung over to extend the supporting surface of the article, for example, to convert the chair or settee into a bed.

Broadly, the present invention provides a bed-chair or bed settee or like article having an extending supporting surface of the kind referred to, characterized in that after a predetermined initial swing-over movement of an extension section in relation to the main frame of the article, one or more members on the swinging extension automatically effect the projection of legs beneath the main frame in which latter the said legs are normally housed. The invention will hereinafter be described with particular reference to a bedchair or bed settee.

Means are provided to effect a delay in the movement of the leg-operating members until the predetermined point in the swing of the extension section is reached. Preferably, the means provided are such that the leg-operating members remain stationary during the initial swing-over movement and that after such initial movement the axis of pivoting of the extension section during the initial movement is transferred to a lower axis of pivoting, after which transfer action the leg-operating members operate to effect extension of the normally concealed bed-legs. In order to impart rigidity to the extended bed, the leg-operating members initiate or effect the projection simultaneously of two transverse pairs of legs, one pair at or near the rear of the main frame, forming the rear legs of the extended bed, and the other pair at or near the front of the main frame, forming legs intermediate of the length of the extended bed.

In preferred constructions according to this invention, the usual back of the chair or settee (and arms, if provided) move with the swing-over extension section and the main frame of the chair or settee is provided with a separate upright member which is normally disposed behind the chair or settee back and which forms a head board when the chair or settee is converted to bed-like form.

Hitherto bedchairs and bed settees have generally been constructed so that the main frame remains resting upon its own legs when converted into a bed. In such constructions, a comfortable seat height above the floor level results in a bed surface which is rather lower than that of the

average bedstead. Alternatively, if provision is made for a bed surface of usual bedstead height, the seating surface of the chair or settee is uncomfortably high. The improved constructions according to this invention obviate these disadvantages by providing both a bed surface and a chair or settee seating surface at comfortable heights above floor level. In order to achieve this desirable result, the projection of the bed-legs is caused to elevate the main frame into a position in which a horizontal supporting surface provided on said main frame is brought into alignment with a second horizontal supporting surface provided on the underside of the swing-over extension section, thereby providing a full-length supporting surface for mattresses and bed-clothing.

The leg-projecting mechanism is housed in the main frame of the chair or settee and the leg-projecting movements thereof are initiated through the agency of the leg-operating members carried by the extension section after a predetermined initial swinging movement of said section. The bed-legs may be of collapsible form, in which case they are preferably housed in the collapsed condition solely within box-like structures provided in the main frame, or the bed-legs may be of rigid form, in which case they are housed out of sight when the article is in chair or settee form partly within the main frame and partly within the extension section which rests upon said frame.

In addition to the bed-legs being of collapsible or rigid form, the leg-projecting mechanism may be constructed in several ways, examples of which are hereinafter more particularly described.

It will have been understood from the foregoing description that the term "bed-legs" is applied to movable legs carried by and adapted to project below the main frame so as to elevate same. When the extension section has been fully swung over, with consequent elevation of the main frame and the projection of the bed-legs, the chair or settee back may form the support for the foot end of the bed, or alternatively extensible front or foot-end legs may be housed in the extension section, which are automatically projected to an operative position when the said section is swung over.

The main reason for providing for a delay in the leg-projecting movement while the extension section is swung through a predetermined initial movement, is to make it an easy task for the extension section to be swung up vertically and

thereafter to take advantage of the weight of the pivoted section to exert a leg-projecting effort, such effort being aided, if desired, by the pulling power of springs associated with the leg-projection mechanism, as will be apparent from the description of particular constructions which follow. For the same reason, the actuating mechanism is also arranged so that when converting a bed into a chair or settee a predetermined initial swinging movement of the extension section must be made before the retraction of the bed-legs is initiated or effected.

The accompanying drawings, which illustrate various embodiments of the invention, show clearly the comparatively large space provided below the seat of the chair or settee in which the bed-clothing may be loosely accommodated, in addition to flock or other mattress pads which are preferably laced to the bed-supporting surface, this latter being composed of two wire spring-mattresses, one on the main frame and the other on the extension section.

Figures 1 to 8 of the drawings show a construction of bedchair employing jointed bed-legs which are housed in the collapsed condition solely within the main frame, Figure 1 being a pictorial view of the chair showing how closely it resembles in appearance an ordinary upholstered armchair, whilst Figure 2 shows the extended bed (without flock mattresses or bed-clothing) and illustrates the natural bed-like appearance which the article presents. Figure 3 is a part-sectional side view of the article in chair form. Figures 4 and 5 are part-sectional fragmentary front views, the sections being taken on lines IV—IV; V—V respectively of Figure 3. Figure 6 is a longitudinal section of the article in bed-form. Figure 7 is a fragmentary sectional plan on line VII—VII of Figure 6 and Figure 8 is a sectional view of one of the erected jointed bed-legs to an enlarged scale.

Figure 9 is a detail vertical sectional view taken on the line 9—9 of Figure 8.

In the construction of bedchair illustrated in Figures 1 to 8, the same comprises a chair base designated generally as A and a seat unit B, the base A includes a main frame which normally rests upon the floor and has four jointed collapsible legs associated therewith, said legs being hereinafter referred to as "bed-legs", and which are housed in a pair of side members in the form of boxes or housings 2 having open bottoms 3. A wire mattress support 4 extends between side members or boxes 2 and an upright member 5 forms the head board of the bed when the article has been converted into bed-form. The seat unit or extension section B comprises a pair of upholstered arms 6, an upholstered back 7, and a wire mattress support 8 having an upholstered seat 9 at its upper side. Said support 8 extends transversely between a pair of closed-in side boxes 10 which latter extend vertically above and below the level of the mattress 8, the upper parts of said boxes 10 being enclosed within the upholstered arms 6. In this construction the boxes 10 serve only to house the auxiliary front-end legs used when the chair is extended to bed-form. The use of these auxiliary legs is optional and if not required there is no necessity to employ the boxes 10, any other suitable side members being then provided.

The chair base or main frame A and the seat unit or extension section B are connected together solely by means of a pair of hinge bars 11, one at each side of the chair, said bars 11 being

hinged to the boxes 2 of the main frame A at pivots 12, and to the boxes 10 of the extension section B at pivots 13.

The wire mattress 4 of the main frame A is resiliently mounted for use as bed-supporting surface by being suspended on tension springs 14 anchored to housings 15 and secured to the walls of the boxes 2. Similarly, in order that the wire mattress 8 of the extension section B shall yield when the seat 9 is sat on, rods 16 are provided which rest upon compression springs 17 carried in housings 18 secured to the walls of the boxes 10. When the section B is swung over to form a bed extension, the mattress 8 also yields to any weight imposed thereon by reason of the rods 16 then bearing down upon the compression springs 19 carried in housings 20 also secured to the walls of the boxes 10.

The collapsed bed-legs 21 and the leg-projecting mechanism associated therewith are housed in each of the open-bottom main-frame boxes 2, each leg consisting of a pair of tubes 21a—21b forming upper and lower sections connected together by a pivoted knee joint 22, the upper tube 21a being anchored by a pivot connection 23 to the roof 24 of the box 2 whilst the lower tube 21b is anchored by a pivot 25 to a longitudinal hollow connecting bar 26 which joins the two legs on one side of the chair together and has knobs 27 for supporting the bar 26 above floor level. In order to ensure equal collapsing and erecting movement of the bed-legs, worm sectors 21c are secured to the bottom sections of the half-legs 21b which co-operate with a spindle 26a rotatably mounted within the hollow bar 26, the opposite ends of the spindle 26a having worm threads or pinions 26b adapted to mesh with the sectors 21c. Transverse connection bars 28 join together the two side bars 26 on opposite sides of the frame which constitutes the base of the chair which rests on the floor. Within each tubular leg section 21a—21b is housed a tension spring 29, anchored at the knee-joint end thereof to a plug 30 and at the opposite end to an anchorage pin 31 which is eccentrically disposed in relation to the axis of swinging of the half-leg 21a—21b about the pivot 24 or 25 respectively that the springs 29 function to assist the legs in moving from the collapsed to the extended position. The leg-operating mechanism consists of a system of pivoted linkage comprising a main link 32 pivoted to the lower end of the hinge bar 11 and to a straight lever 33 pivotally anchored at 34, a connecting link 35 extending between the lever 33 at the cranked lever 36 which is pivotally anchored at 37. From the levers 33 and 36 outwardly extend in opposite directions links 38—39 respectively which are connected to the upper parts of the upper half-legs 21a. It will be apparent from Figures 3 and 6 that when the hinge bars 11 swing about pivots 12, the linkage operates to erect the collapsed legs, the leg springs 29 assisting in the action. It will also be quite clear from the drawings that during the initial swing-over movement of the extension section B, said section swings about the pivots 13, without moving the hinge bars 11. When the section B reaches the position indicated in chain-dotted lines in Figure 3, the floors 49 of the boxes 10 abut against the hitherto stationary hinge bars 11 so that during the continued swinging movement of the section B, said bars 11 move with the section and thus actuate the leg-projecting mechanism. In other words, the

axis of swinging of section B is transferred from pivots 13 to pivots 12.

During the initial swing-over movement of extension section B about pivots 13, the links 41 swing idly about the upper ends of the stationary hinge bars 11 without imparting much swinging movement to the spring-controlled cranked levers 42, so that the front-end legs 43 which slide within tubular housings 44 in the chair back 7 are not projected beyond the top of said back 7. When the section B and hinge bars 11 swing about pivots 12, however, the links 41 and levers 42 operate to project the front-end legs 43 to the position shown in Figure 6.

15 It will be observed that ample space for the storage of flock mattresses (which are preferably laced to the wire mattresses 4, 8) and of all the necessary bedclothes is afforded in the chair within the space between the wire mattresses 4, 8. Figure 9 illustrates clearly the extent to which the extension section B can be swung over before the leg-projecting movements are effected, whilst Figure 10 shows how, after the predetermined initial swing-over movement has been effected, 25 the continued swinging of the section B is accompanied by the projection of the bed-legs. The opening at the front of the chair between the wire mattresses 4 and 8 is normally covered by a flexible curtain 45.

30 We claim:

1. An article of furniture for use as a chair or bed, including: a chair base comprising a frame adapted to rest on the floor, side members, a transverse mattress support connecting the side members, elevating means respectively connected to the frame and side members; vertically disposed hinge bars pivotally connected to said side members and operatively connected at their lower ends with said elevating means; a seat unit 35 including a transverse mattress support, means pivotally connecting the seat unit with the hinge bars above their points of pivotal connection with the side members, and means carried by the seat unit for engaging the rear side of the hinge bars as the seat is tilted to overturn forwardly and downwardly to move said bars and actuate said elevating means to raise the mattress support of the chair base so that it will be in horizontal alignment with the mattress support of the overturned seat.

40 2. An article of furniture for use as a chair or bed, including; a chair base comprising a frame adapted to rest on the floor, side members, a transverse mattress support connecting the side members, elevating means connected to the frame and side members and including jointed inwardly collapsible leg members; vertically disposed hinge bars pivotally connected to said side members and operatively connected at their lower ends with said elevating means; a seat unit including a transverse mattress support, means for pivotally connecting the seat unit with the hinge bars above their points of pivotal connection with the side members, and means carried by the seat unit for engaging the rear side of the hinge bars as the seat is tilted to overturn forwardly and downwardly to move said bars and actuate the collapsible legs of said elevating means to raise the mattress support of the chair base so that it will be in horizontal alignment with the mattress support of the overturned seat.

45 3. An article of furniture for use as a chair or bed including; a chair base comprising a frame adapted to rest on the floor, side members in the

5 form of housings having outer and inner walls, a transverse mattress support connecting the inner walls, a vertical back wall at the rear end of said side members, elevating means connected to the frame and the side members and including jointed legs connected by links with levers pivoted to the walls of the side members; vertically disposed hinge bars pivotally connected to the front ends of said side members and operatively connected at their lower ends with said elevating means; a seat unit including a transverse mattress support having an upholstered seat and back on its normally upper side, means for pivotally connecting the front end of the seat unit with the bars above their points of 15 pivotal connection with the side members, and means carried by the seat unit for engaging the rear sides of the hinge bars as the seat unit is tilted to overturn forwardly and downwardly to move said bars and actuate said elevating means 20 to raise the mattress support of the chair base so that it will be in horizontal alignment with the mattress support of the overturned seat.

4. An article of furniture for use as a chair or bed, including; a chair base and a seat unit; 25 vertically disposed hinge bars pivotally connecting the front ends of the chair base and seat unit; a frame in said chair base, legs connected at their lower ends to the frame, lower boxes constituting the sides of the chair base supported on the upper ends of the legs and concealing the same, a transverse mattress support connecting the lower boxes; upper boxes forming arm members for the seat unit, a transverse mattress support connecting the upper boxes, means 30 mounted in said lower boxes and cooperating with said legs for elevating said lower boxes relative to said frame; actuating means connecting the last named means with the lower ends of said hinge bars; and means carried by the seat unit 35 and engaging the hinge bars above their pivotal connection with the seat unit as it is tilted to overturn forwardly and downwardly to operate the hinge bars and said actuating means connected therewith and thereby elevate the lower 40 boxes and the mattress support carried thereby 45 into horizontal alignment with the mattress support of the upper boxes when the forwardly tilted seat has been completely overturned.

5. An article of furniture for use as a chair or bed, including; a chair base comprising, a frame, lower boxes forming side members at each side of the frame, collapsible jointed legs having their lower ends pivotally connected to said frame and also having their upper extremities pivotally connected to said lower boxes and a transverse mattress support carried by said boxes; a seat unit comprising upper arm boxes, a transverse mattress support carried by said arm boxes; vertically disposed hinge bars pivotally connecting 55 said lower and upper boxes, link and lever means concealed in said lower boxes and cooperating with said jointed legs for elevating the said lower boxes; actuating means connecting the link and lever means with the lower ends of said hinge 60 bars; and means carried by the seat unit for engaging the hinge bars as the seat unit is tilted to overturn forwardly and outwardly to operate said hinge bars and actuating means and elevate the mattress support carried by the side 65 members of the chair base into horizontal alignment with the mattress support of the overturned seat.

6. An article of furniture for use as a chair or bed, including; a chair base comprising a 70 75

frame adapted to rest on the floor, side members connected by an upright back wall and a transverse mattress support, a pair of jointed inwardly collapsible bed legs at opposite sides 5 of the frame and having their lower ends connected therewith and their upper ends connected to the side members; a seat unit including hollow arms, a back, and a transverse mattress support; link and lever means for erecting the legs 10 and elevating said side members, and vertically disposed hinge bars pivoted in the side members, said hinge bars having the seat unit pivotally connected thereto at one side of the pivot, and also having a pivotal connection at the 15 other side of the pivot with the link means, whereby when the seat unit is tilted to overturn forwardly and a portion thereof engages and turns the hinge bars the latter will elevate the side members through the legs and the mattress support of the chair base will be elevated into 20 horizontal alinement with the mattress support of the seat when the back of the seat unit is overturned.

7. An article of furniture for use as a chair 25 or bed, including; a chair base comprising a frame adapted to rest on the floor, side members connected by an upright back wall and a transverse mattress support, elevating means connecting the frame and the side members for raising and lowering said side members and back wall; vertically disposed hinge bars pivotally mounted at the front end of said side members so that their lower ends below the pivot may 30 swing inwardly; a seat unit pivotally connected to the hinge bars above the pivotal connection of the hinge bars with said side members whereby said seat unit may be tilted forwardly to a vertical position without moving the hinge bars, actuating means connecting the lower ends of 35 the hinge bars with said elevating means, means on the seat unit for engaging the hinge bars as the seat unit moves from a vertical position to a horizontal position thereby to move said hinge bars and actuate said elevating means for raising 40 the side members, and a mattress support in the seat unit adapted to be horizontally alined with the mattress support on the side members of the chair base when the side members are elevated and the seat unit is overturned.

50 8. An article of furniture for use as a chair or a bed, including; a chair base comprising a frame having a pair of bar members, a pair of bed-leg members for each bar, said leg members each comprising medially jointed upper and lower sections, means for pivotally connecting the lower section of each jointed leg with each bar, an inverted relatively shallow box overlying each bar member, means for pivotally connecting the upper section of each leg with the transverse wall 55 of each box, a mattress support carried by said boxes; a seat unit including a back, and hollow arm members having top, bottom and side walls and connected by a transverse support provided on one side with an upholstered seat and whose 60 other side forms a mattress support; link and lever means for actuating said upper and lower sections of the legs to cause their erection and the elevation of the side boxes; actuating means pivotally connected with said side boxes near 65 their front end and connected with said link and lever means, means for pivotally mounting the seat unit on said actuating means above the latter's pivotal connection with the side boxes, said seat member being tilttable forwardly on the 70 means which connects it with the actuating 75

means and having means thereon, which during a portion of the tilting movement of the seat, engages said actuating means thereby to energize the same and elevate the side boxes of the chair base so that the transverse mattress support 5 carried by the said boxes of the chair base becomes horizontally alined with the transverse mattress support of the seat unit.

9. An article of furniture for use as a chair or a bed, including; a chair base comprising a 10 frame having a pair of bar members, a pair of bed-leg members for each bar, said leg members each comprising medially jointed upper and lower sections, means for pivotally connecting the lower section of each jointed leg with each 15 bar, an inverted relatively shallow box overlying each bar member, means for pivotally connecting the upper section of each leg with the transverse wall of each box, a mattress support carried by said boxes; a seat unit including a 20 back and hollow arm members having top, bottom and side walls and connected by a transverse support provided on one side with an upholstered seat and whose other side forms a mattress support, and means for actuating said leg members 25 to elevate the side boxes, said means including a pair of normally vertical hinge bars mounted on transverse pivots in the front end of said box members, a transverse seat pivot in the front end of each hollow arm member and passing through 30 the hinge bars above their pivots in the boxes, interconnected lever means pivotally connecting the upper leg sections with the boxes, link means connecting the lever means with the hinge bars, said hinge bars adapted to be engaged at 35 their upper edges by the bottom walls of the arm members of the seat when the latter is tilted forwardly past vertical position to overturn and move the hinge bars on the transverse pivots in the boxes and thereby move the said link 40 means to bring the upper and lower leg sections into vertical alinement and simultaneously elevate the boxes and mattress support carried thereby into horizontal alinement with the underside of the support between the arm members when the back of the seat unit reaches fully 45 overturned position.

10. An article of furniture for use as a chair or bed, including; a chair base comprising a frame adapted to rest on the floor, side members connected by an upright back wall and a transverse mattress support, elevating means connecting the frame and the side members for raising and lowering said side members and back wall; vertically disposed hinge bars pivotally mounted at the front end of said side members so that their lower ends below the pivot may swing inwardly, links connecting the lower ends of the hinge bars with said elevating means, a seat unit pivotally connected to the hinge bars above the pivotal connection of the hinge bars with said side members whereby said seat unit may be tilted forwardly to a vertical position without moving the hinge bars, means on the seat unit for engaging the hinge bars as the seat unit moves forwardly from a vertical position to a horizontal position thereby to move said hinge bars and said links to actuate said elevating means for the side members, a mattress support in the seat unit adapted to be horizontally alined with the mattress support of the chair base when the latter is elevated, spring controlled projectible leg members in the seat unit normally housed within the same when the article of furniture is used as a chair, and link and lever means connected with 70 75

said hinge bars near their upper extremities and adapted to project said leg members of the seat unit to engage with the floor when the seat unit is moved to horizontal position.

- 5 11. An article of furniture for use as a chair or bed, including; a chair base comprising a frame adapted to rest on the floor, side members connected by an upright back wall and a transverse mattress support, elevating means connecting the frame and the side members for raising and lowering said side members and back wall; vertically disposed hinge bars pivotally mounted at the front end of said side members so that their lower ends below the pivot may 10 swing inwardly; links connecting the lower ends of said bars with said elevating means a seat unit pivotally connected to the hinge bars above the pivotal connection of the hinge bars with said side members whereby said seat unit may be 15 tilted forwardly to a vertical position without moving the hinge bars, means on the seat unit for engaging the hinge bars as the seat unit continues to move forwardly from a vertical position to a horizontal position thereby to move said 20 hinge bars and said links to actuate said elevating means for the side members, a mattress support in the seat unit adapted to be horizontally aligned with the mattress support of the chair base when the latter is elevated, spring controlled 25 projectible leg members in the seat unit normally housed within the same when the article of furniture is used as a chair, angular levers pivoted in the arms of the seat unit and connected to said projectible leg members, springs connected to said levers tending to eject said leg members, and links connecting said levers with the hinge bars, whereby, when the seat unit is tilted fully forward, the legs will be moved out of the back of the seat and into floor engaging 30 position.

- 40 12. An article of furniture for use as a chair or bed, including; a chair base comprising a frame adapted to rest on the floor, side members, a transverse mattress support connecting the 45 side members; elevating means between the side members and the frame for lifting said side members, said elevating means comprising opposite pairs of collapsible legs, said legs each including upper and lower sections pivotally connected together at their inner ends, pivotal connections between the upper ends of said upper sections and the side members, pivotal connections between the lower ends of the lower sections and said frame, said last named pivotal connections 50 including pinions forcing each other and engaging with right and left worm threads located at opposite ends of a common shaft journaled in said frame, link and lever means pivotally connecting the upper sections of each pair of 55 legs, and a main actuating link for said link and

lever means; hinge bars pivotally connected to said side members and operatively connected at their lower ends with said main actuating link; a seat unit including a transverse mattress support, means pivotally connecting the seat unit with the hinge bars above their point of pivotal connection with the side members, and means carried by the seat unit for engaging the rear side of the hinge bars as the seat is tilted forwardly and downwardly to move said bars and thereby operate said main actuating link thereby to move said link and lever means to elevate the side members and bring the mattress support carried thereby into horizontal alinement with the seat unit of the mattress support. 15

13. An article of furniture for use as a chair or bed, including; a chair base comprising a frame adapted to rest on the floor, side members, a transverse mattress support connecting the side members; elevating means for said side members, comprising, pairs of collapsible leg members between the side members and the frame for elevating the side members, each of said leg members being of hollow tubular formation and comprising upper and lower sections pivotally connected at their inner ends, means for pivotally connecting the upper ends of the upper sections to the side members, means for pivotally connecting the lower ends of said lower sections to the frame, a plug anchored in the inner end of each of said leg sections, spring anchoring posts respectively carried by the side members and the frame and located in the upper and lower ends of said upper and lower hollow leg members, and springs within the hollow leg members, said springs having their inner ends secured to said plug members and their outer ends connected to the upper ends of said spring anchoring posts on the side members and frame, whereby, the outer ends of the springs are anchored eccentrically to the pivots for connecting the upper and lower ends of the leg members respectively with the side members and frame; actuating means for the elevating means including said hollow leg members, vertically disposed hinge bars pivotally connected to said side members and operatively connected at their lower ends with said actuating means; a seat unit including a transverse mattress support, means for pivotally connecting the seat unit with the hinge bars above their points of pivotal connection with the side members, and means carried by the seat unit for engaging and moving the hinge bars as the seat is tilted forwardly and downwardly to move said bars and operate the elevating means including the spring tensioned leg members to bring the mattress supports of the chair base and seat into horizontal alinement. 55
